(57) **CLAIM**

The ornamental design for a safety razor, as shown and described.

DESCRIPTION

FIG. 1 is a front perspective view of a safety razor showing my new design;

FIG. 2 is a rear perspective view thereof;

FIG. 3 is a front view thereof, the rear view being a mirror image of FIG. 3;

FIG. 4 is a top plan view thereof;

FIG. 5 is a bottom plan view thereof;

FIG. 6 is a right side elevational view thereof;

FIG. 7 is a left side elevational view thereof;

FIG. 8 is an enlarged cross-sectional view taken along line 8—8 in FIG. 3;

FIG. 9 is an enlarged cross-sectional view taken along line 9—9 in FIG. 3;

FIG. 10 is an enlarged cross-sectional view taken along line 10—10 in FIG. 3;

FIG. 11 is an enlarged cross-sectional view taken along line 11—11 in FIG. 4; and,

FIG. 12 is a left side elevational view of the safety razor with a cover.

The broken line in FIG. 12 is shown for illustrative purposes only and forms no part of the claimed design.
